UNITED STATES PATENT OFFICE.

JAMES C. WALKER, OF WACO, TEXAS.

ROTARY ENGINE.

SPECIFICATION forming part of Letters Patent No. 611,536, dated September 27, 1898.

Application filed December 27, 1897. Serial No. 663,784. (No model.)

To all whom it may concern:

Be it known that I, JAMES C. WALKER, residing at Waco, in the county of McLennan and State of Texas, have invented a new and 5 Improved Rotary Engine, of which the following is a specification.

This invention, which relates generally to improvements on the form of engine disclosed in my Patent No. 515,631, dated February 17, 10 1894, more particularly refers to an improved means for operating the abutment-slides and the inlet-valve devices disclosed in my co-pending application filed December 27, 1897, Serial No. 663,783.

15 This invention in its most essential features differentiates from the construction in my other application in the peculiar relation and arrangement of the automatic adjustable centrifugally-operated devices for operating the 20 connections for the sliding or throttled valve of the steam-chest.

The invention consists in the peculiar arrangement of parts, such as will be first described in detail and then be specifically 25 pointed out in the appended claims, reference being had to the accompanying drawings, in which—

Figure 1 is a side elevation of my improved engine, parts being shown in section. Fig. 30 2 is an enlarged vertical section taken on the line 2 2 of Fig. 1. Fig. 3 is a transverse section on the line 3 3 of Fig. 2. Fig. 4 is a detail view of one set of the abutment-slide-operating rock-frame. Figs. 5 and 6 are respectively a top and inverted plan view of 35 the mechanism for operating the inlet-valve-lever devices. Figs. 7, 8, and 9 are detail views illustrating a modified construction of abutment and valve operating devices. Fig. 40 10 is a detail view illustrating the shifting valve for the steam-inlet and the exhaust and inlet ports for the cylinder.

In its general structure this form of engine 45 comprises a nest of cylinders, preferably four, arranged in two sets, designated by B B' and B² B³, which are formed in sections joined together, mounted upon suitable bases and provided with offtake devices at the lower end for the escape of the products of the condensations, the same as in my other application referred to. In the present form the cylinders each have an annular steam-chamber

and a sliding abutment arranged at the upper end, which abutments of the several cylinders are disposed in the same radial alignment. The shaft is also provided with a number of concentric pistons, one for each chamber, which pistons for each set of cylinders are disposed at diametrically opposite points, and, if desired, the arrangement of the pistons in the two sets may be alike, so as to take live steam in two cylinders at one time, as shown, or they may be arranged alternately, so that the shaft of the engine may receive a live-steam force at each quarter of its revolution.

In the present structure the operating-disks which carry the cam devices for operating the abutment-slide valves are also fixedly mounted on the shaft C between the 70 inner pair of cylinders. The disks, one of which is employed for each set of cylinders, consist of a solid body portion d, fixedly held on the shaft C. (See Figs. 2 and 3.) This body portion has three operating parts—a 75 middle circular section d⁵, which serves as a guide, and reduced annular portions d⁶ and d⁷ on opposite sides, which terminate in diametrically opposite projecting arrow-like heads d⁸ and d⁹, the purpose of which will presently appear.

c⁵ c⁶ designate pendent levers guided in suitable bearings, the upper ends of which terminate in four portions c⁷ c⁸, which respectively connect with the abutment-slide-operating-lever devices, one set of which is illustrated in detail in Fig. 4. Each set of these devices comprises a shaft c, journaled in suitable bearings, on which one end of the rocker-arms c' c' and c² c³ are loosely journaled, their outer ends being pivotally secured to the lift-arms c¹⁰ of the abutment-slide frame c¹² for the cylinder B² and the arm c¹⁴ of the frame c¹⁵ for the abutment-slide for the cylinder B³.

The lower ends of the pendent levers c⁵ c⁶ carry a crescent-shaped frame d⁸, and such lower ends and frame are also strongly braced by the members d²², as shown in Fig. 2.

In each end of the frames d⁸ is journaled a friction-roller, which rollers operate against the side of the guide-casing d⁹, which is provided to keep the contact-piece d⁸ in proper position and also to take up the stress of the

shock when the member d^6 or d^7 comes in contact with its coincident frame member d^8 , such arrangement of parts allowing the levers c^5 c^6 to slide freely without undue lateral strain in their bearings.

The casing d^2 , as will be clearly seen in Fig. 3, has a central division member whereby a separate guiding-compartment is provided for each lever c^5 c^6 , and such casing is secured to the side of the cylinder B^2 by suitable brackets d^9 .

H^5 indicates a cog-wheel fixedly secured on the drive-shaft c , which meshes with a horizontal cog-gear H^2 , fixedly secured on the lower end of the vertical guide-shaft H , journaled in suitable bearings, the lower end having ball-bearings on the bracket H' , while its upper end carries a centrifugal ball-governor mechanism and two cam-equipped disks, the detail construction of which is more clearly shown in Figs. 5 and 6.

As the construction of cam devices on both disks H^6 and H^7 is alike, a detail description of such devices of one disk will suffice for both.

The disk H^6 , the upper and lower faces of which are shown in Figs. 5 and 6, respectively, has an annular upwardly-projected outer rim h^{21} , which constitutes the perimeter of the disk. The inner edge of such rim at a suitable point has an inwardly-projecting triangular distention a^{12} , at the apex of which a subtended cross-bar a^{13} is disposed, which bar is held a short distance away from the said apex, whereby an intermediate guide-passage is formed for the pendent end of the rod h^7 , which connects with the valve devices for the cylinder B^2 and the rod h^6 for operating the similar devices for cylinder B' , the valve-operating devices for cylinders B and B' being operated by like rods h^{70} and h^{60} , which engage the upper disk and cam devices h^7 . At this point it should be stated that when disk H^6 is turned with the shaft H the pendent ends h^{10} of the rods h^6 and h^7 will alternately contact with the portion a^{12} and be drawn in toward the center of the disk until the ends h^{10} reach the apex of the portion a^{12} , when the inward movement of such rods h^6 and h^7 is checked by the stop or cross-bar a^{13} and left in that position until the triangular cut-off head a^{11} engages them, which will serve to move such rods h^7 and h^6 outward again, such alternate movement of the rods effecting the reciprocal movement on the respective slide-rods, as will hereinafter more fully appear.

Two cut-offs a^{11} and a^6 are provided for each disk H^6 and H^7 , which have their shanks a^4 pivotally joined to the disk adjacent its center, such shanks being guided under the segmental arms a^{10} .

At diametrically opposite points the disk h^6 has elongated apertures a^{14} , in which governor weight-blocks H^3 are held to slide on suitable guide-rods, which weights are held

normally against undue centrifugal force by the spring h^5 .

At a point midway the apertures a^{14} the disk at one side has a radial groove a , in which is held to slide a lighter weight a' , which connects with the blocks H^3 by pivotal levers a^3 a^2 and with the shanks of the cut-offs by the levers a^3 .

H^{20} indicates a cap fixed on the upper end of shaft H , to which rods h^{17} are attached, which carry the governor-balls.

h^{15} indicates a band held to slide upon the upper end of the shaft, which is connected with, raised, and lowered by the centrifugal attachment of the governor-weights.

h^{21} indicates a ring placed above the band h^{15} , which rides up and down with the said band. This ring h^{21} has two pendent rods on opposite sides of the shaft H , which extend down through holes in the two disks H^6 and H^7 , and connect with the ring k intermediate the disks H^6 and H^7 and ring b below the lower disk H^6 , which rings k and b , owing to their connection with the ring b^{21} , move up and down in unison with the band h^{15} .

The ring h is connected to the weight-blocks H^3 by link-rods h' , while the ring k is similarly connected by the link-rods h^2 with the weights H^3 of the upper disk H^7 .

By arranging and combining the several parts constituting the valve-operating mechanism as described a double automatic governor means for regulating the cut-offs is provided having a direct centrifugal action and an indirect adjustment through the medium of the ball-governor-operated devices.

While I prefer to use the duplex mechanism shown, it is manifest the ball-governor devices may be omitted without rendering the cut-offs inoperative.

The abutment slides or valves in practice are made of polished steel plates, the lower half of which are made circular to exactly fit the bore of the cylinders and are held to slide in a narrow groove in the cylinder-wall and the abutment-casing. The upper portion of the abutments may be made square, as shown, or circular, if desired.

In operation when the steam is turned on into any one or set of cylinders the shaft and cam-disks are caused to revolve. When the extension d^{70} engages its respective crescent-frame d^3 , the lever c^5 is forced upward, its forked ends lifting the abutment-slide frame c' and through it the abutment-slide F^7 of the cylinder D^3 . After the member d^{70} passes its frame d^3 the lever c^5 will gravitate back and in consequence bring the slide F^7 back to act as a wall or abutment, and as the disk d continues in its rotation its member d^{60} engages the frame d^3 of the lever c^6 , lifts it and the slide F^6 of the cylinder B^2 , which slide also turns to its cut-off position by gravity. During this operation the disks H^6 and H^7 are revolved by the rotation of shaft H , which disks reciprocate the several rods which connect with the

slide-valves heretofore referred to. The rod h^7 of the lower disk H^6 is connected to the crank c^{20} on the vertically-disposed rock-shaft c^{15} , which has a second crank c^{21} , connected by the link-arm c^{22} with the slide-valve c^{25} , it being obvious that when the arm h^7 is reciprocated a reciprocal action is imparted to the valve c^{25} . In this structure a slide-plate H^{23} is mounted in the steam-chest between valves c^{25} and the inlet and exhaust ports of the cylinder, which is connected through suitable levers with the double rock-shafts R and R' , having a suitable handle R^2 . In the present form of valve-operating means but a single supplemental valve is employed for each steam-chest. Its movement may be readily reversed by the reverse action of the cam disk.

It will be understood from the drawings that the devices which operate the reciprocating valves of the cylinders B , B' , and B^2 are exact duplicates of and operated precisely like the devices disclosed for operating the valve c^{25} . The mechanisms at the left of Fig. 1 for operating the abutment-slide valves for cylinders B and B' being duplicates of those described for operating slides F^6 and F^7 , a detailed description thereof is deemed unnecessary.

During operation when the disks H^6 and H^7 are revolved the weights H^3 H^3 are forced outward by centrifugal action and through the medium of connecting-levers drives the weights a' inward, which in such movement forces the cut-offs a^{11} and a^6 closer to the triangular rim-section a^{12} , and thus shortens the time of admission of live steam.

When the engine slackens its speed, the several weights are forced by their pressure-springs which moves the heads a^{11} and a^6 correspondingly away from the members a^{12} and increases the time of steam admission. By a union of the governor devices carried on the disks H^7 and H^6 and the ordinary governor on the end of shaft H the action of the cut-offs is rendered more uniform and positive.

Figs. 7 and 8 illustrate a modified form of devices for operating the inlet-valve and sliding abutments. In this construction the cam devices on the drive-shaft are dispensed with and the abutment-slides and lever mechanism operated by cams fixed to the under side of the disks H^6 and H^7 , which carry the cam devices on their upper faces for operating the inlet-valve levers the same as in the construction shown in Fig. 5. In this form of devices a segmental cam c^{17} is pivotally secured to the under side of the disk H^6 and a similar cam C^{28} to the under side of the disk H^7 . These cams have horizontal pendent bevel faces which are adapted to engage the upturned ends of the rods c^8 , c^{14} , c^{18} , and c^{19} , each of which connects with suitable rock-shaft devices connected with the several abutment-slides for the cylinders B , B' , B^2 , and B^3 .

As all of such rock-shaft devices are constructed and operated alike, I will describe one in detail. The rod c^8 connects with the crank-arm c^{70} on the horizontal rock-shaft c^{60} , which has an oppositely-projecting crank-arm c^{50} , connected by a link-rod c^{40} with the rearwardly-extending crank c^{30} of a rocker lift-frame c^{20} . In operation as the disk H^6 rotates the shaft c^{60} , through the medium of the cam c^{17} , will be rocked in one direction to lift the frame c' , it being rocked to the reverse direction by the reverse movement of the frame c' , imparted by the gravity drop of slide F^6 .

While I have not illustrated the inlet-valve-operating devices in Figs. 7 and 8, it should be stated that their arrangement is precisely like those indicated in Figs. 1, 2, and 4 of the drawings.

Further modifications and changes of details may be made without departing from the scope of my invention.

Having thus described my invention, what I claim, and desire to secure by Letters Patent, is—

1. In a rotary engine, the combination with the cylinders; the drive-shaft; the abutment-slides, and means for automatically operating such slides; of a cut-off-valve mechanism for the cylinders; lever devices for operating a reciprocating action of the said valve mechanisms; the drive-shaft H , geared with the main drive-shaft C ; the centrifugally-operating cut-off devices mounted on the shaft H , and held to engage and impart a reciprocating action to the valve-shifting-lever devices, all being arranged as shown and described.

2. In a rotary engine of the character described; the combination with the cylinder; the drive-shaft; the automatically-operated sliding abutment and the reciprocating valve mechanism for the cylinder; a rock-shaft having a crank member connected to the reciprocating valve, said rock-shaft also having a second crank member; an operating-rod connected with said second crank member; a rotary disk geared with the main drive-shaft, said disk having positive means for intermittently engaging the rod and pulling it in one direction; and speed-governed means for moving such rod to a reverse direction, substantially as shown and for the purposes described.

3. In a rotary engine as described, a reciprocating valve-operating mechanism, comprising a rock-shaft connected with the valve, a supplemental shaft geared with and driven by the main drive-shaft, a disk held upon such shaft to turn therewith, said disk having a fixed inlet cut-off member a^{12} , and centrifugally-operated cut-offs a^6 , a^{11} , and a lever having a crank member connected with the valve-operating crank-shaft, and a pendent portion adapted to be alternately engaged by the fixed inlet member a^{12} and movable

cut-off members a^6 and a^{11} , of the rotary disk, all being arranged substantially as shown and for the purposes described.

4. In a rotary engine as described; the combination with the drive-shaft and the reciprocating cut-off-valve devices; of the shaft H, geared with the drive-shaft; the disks H⁶ H⁷ having fixed inlet cut-off members and pivotal cut-offs; means for holding the said

cut-offs normally against centrifugal movement, and the centrifugal governor devices carried on the end of the shaft H and connected with the pivotal cut-offs, all being arranged substantially as shown and described.

JAMES C. WALKER.
